UNITED STATES PATENT OFFICE

FRED J. CLEMENS, OF EAST HAVEN, CONNECTICUT, ASSIGNOR TO THE WILLIAM SCHOLL HORN COMPANY, OF NEW HAVEN, CONNECTICUT

PIPE WRENCH

Application filed April 15, 1930. Serial No. 444,411.

This invention relates to pipe wrenches and more particularly to a type of the same known as springless pipe wrenches.

The improvements contemplated by this invention are especially adapted for use in a wrench structure similar to that shown and described in an application of William A. Bernard, Serial No. 46,912, filed July 29, 1925, now issued as Patent No. 1,762,324, dated June 10, 1930. One of the principal features of this invention is the provision of means to relieve the pivotal joint between the jaws from shearing strains. Other features are in the provision of jaw movement limiting means, means to permit the rapid release or gripping of the work, and movable jaw guiding and supporting means.

One of the objects of this invention is to provide a generally improved pipe wrench of the above type that is efficient in use, economical to manufacture, compact, and of strong and sturdy construction.

Another object is to provide an improved wrench in which the strains put upon the same are properly distributed, whereby the tendency toward binding, breakage or bending of the parts when in use will be reduced to a minimum.

Another object is to provide an improved wrench that may be readily and rapidly engaged with and disengaged from the work.

A further object is to provide an improved pipe wrench having a minimum number of parts all of which are of rugged construction.

To these and other ends, the invention consists in the novel features and combinations of parts to be hereinafter described and claimed.

In the accompanying drawings:

Fig. 1 is a side view of a wrench embodying the features of this invention;

Fig. 2 is a longitudinal section through the operating parts of the wrench, certain parts not being sectioned for the sake of clearness;

Fig. 3 is a section on line 3—3 of Fig. 2;

Fig. 4 is a section on line 4—4 of Fig. 2;

Fig. 5 is a section on line 5—5 of Fig. 2, and

Fig. 6 is a longitudinal section through the operating parts of the wrench, showing the same in operating position.

A wrench embodying the features of this invention comprises a handle-bar having a handle portion 10 and a jaw portion 11, a jaw 12 having a shank portion 13, a yoke member 14, and a rotatable adjusting nut 15. These parts are assembled together, preferably as shown, the yoke 14 being pivotally secured to the handle-bar by a pivot pin 16. The jaw portion 11 and the jaw 12 are provided with work gripping teeth 17 and 18 respectively that are of the usual form. The shank portion 13 is provided with threads 19, that cooperate with internal threads provided in the nut 15. The toothed portion of jaw 12 is disposed substantially at right angles to the shank 13.

The yoke member 14 is of heavy sheet metal and is bent into an inverted U-shape about the shank 13, with the arms 20 and 21 of the U-shape straddling the sides of the shank 13 and extending downwardly to straddle the handle-bar intermediate the jaw portion 11 and the handle portion 10 thereof. The pivot pin 16 is disposed adjacent the forward or jaw end of the yoke 14. A block 22 is disposed at the rear end of yoke 14, between the arms 20 and 21, and is secured in place by a rivet 23.

Each of the arms 20 and 21 of the yoke member 14 is provided with an opening 24 that is elongated along an arc, the center of which is located at the center of the pivot pin 16. A stud 25 preferably formed integral with the handle-bar, extends outwardly from each side thereof and is adapted to be received in the respective opening 24 of arms 20 and 21 when the same are closed about the bar. The yoke member 14 is also provided with a cutout 26 to receive the nut 15, whereby rotation of the nut, due to the cooperating threads between it and the shank 13, will move the shank 13 in or out of the yoke 14 and jaw 12 toward or away from jaw portion 11, for adjustment of the wrench to suit pipes of various diameters.

The shank portion 13 is vertically retained within the yoke 14 by being supported upon

an upper surface 27 of the handle-bar adjacent the pivot 16, the handle-bar at this point being spaced upwardly above the upper surface of the handle portion 10. This spacing permits the disposition of the block 22 between the rear end of shank portion 13 and the handle portion 10. This block provides the movement limiting means for the yoke in its downwardly swinging movement relative-
ly to the handle-bar about the pivot 16, and for the downward movement of the rear end of shank portion 13 relatively to the yoke 14. The surface 27 is concave in cross-section, the curvature substantially agreeing with the curvature of the under-surface of the shank portion 13 preferably as defined by the diameter of the threads 19, whereby the shank portion 13 with its jaw 12 is guided in its longitudinal movements and retained against lateral movement or twisting with respect to the handle-bar when the wrench is in use. The surface 27 is inclined from a point slightly to the rear of a perpendicular line drawn through the center of pivot 16, forwardly and downwardly toward the jaw 11, the inclination being sufficient to permit the necessary swinging movement of the handle-bar for the proper operation of the wrench. Preferably, the forward end 28 of the upper surface 27 is adapted to engage the under-surface of the shank 13 before the work is properly gripped by the jaws in order that the shank 13 will be forced upwardly into tight engagement with the yoke 14. The arrangement of the inclined surface 27 is such that no binding will occur between the handle-bar and the shank portion 13.

The teeth 17 of the jaw 11 are in alignment and form an obtuse angle with the upper surface of handle portion 10, and an acute angle with the surface 27. The line of teeth is disposed in respect to the pivot pin 16 in such a manner that the same will be tangent to an arc struck from the center of pivot 16 of a radius substantially equal to the distance between the first tooth adjacent the surface 27 and the center of pivot 16. This arrangement insures that the jaw 11 in its swinging movement about pivot 16, will rapidly move toward or away from the work, causing rapid gripping or release respectively of the work, and preventing the jaws binding upon the work.

The studs 25 that extend into and cooperate with the openings 24 in the yoke sides 20 and 21, are adapted to seat against the material of the yoke at the lower ends of the openings 24, when the jaws 11 and 12 are in proper gripping position upon the work, in order to relieve the pin 16 of shearing strains that might be caused by the handle-bar being fulcrumed upon the shank 13, when the point 28 of surface 27 engages the under-surface of the shank. This arrangement also distributes the rotating force imposed upon the

yoke 14 and shank portion 13 over substantially the entire cooperating length thereof when the work is being rotated by the wrench about the axis of the work. The studs 25 and openings 24 also cooperate to form a movement limiting means for the jaws 11 and 12 to prevent undue compression thereof upon the work that might inadvertently crush the same.

The above described wrench structure has been found to be especially strong and sturdy, particularly efficient in use, comparatively inexpensive to manufacture and adapted for use where rapid operation is required. Being of few parts, all of which are of rugged structure, a wrench of this construction insures a minimum of breakage or other damage, even under extreme rough usage, that would impair the usefulness of such a wrench.

What I claim is:

In a pipe wrench, a handle member having a jaw on one end thereof, a threaded shank member having a jaw thereon in opposed relation to said other jaw, an inverted U-shaped yoke member embracing said shank member with the closed upper portion of the U-shape disposed closely adjacent the upper surface of said shank and with an arm thereof extending downwardly along each side of said handle member, said yoke member adjacent one end thereof being pivoted to said handle member by a pivot pin, said yoke member having an arcuately elongated opening in each of the arms of the U-shape thereof, a stud integral with and extending from each side of said handle member and into the arcuate opening in the adjacent arm of said yoke member, which is spreadable to spring over said studs, and a block between the arms of said yoke member adjacent the end opposite the pivoted end thereof and disposed between said threaded shank member and said handle member in line with the elongated openings in said arms and secured to said arms to retain the arm portions of said yoke member at the end opposite the jaw end thereof in spaced apart relation and against spreading and becoming released from said studs.

In witness whereof, I have hereunto set my hand this 10th day of April, 1930.

FRED J. CLEMENS.
